John H. Clark - a Citizen of the United States

Improvement in the Construction & Manufacturing of Coal
and other coke and bondstones for burning Anthracite coal & other fuel which
is to be used in the Radiator or Globe Stove

Date of Patent, May 8, 1834

Certified at Albany July 8, 1834

John H. Clark, referred to in their Letter Patent
and making part of the same containing a description in
the words of the said H. Clark himself of his improve-
ment in the Construction and Manufacturing of cast iron
stones for burning Anthracite coal and other fuel which is
to be used in the Radiator or Globe Stove.

It shall be when these products shall come.

I, John H. Clark, of the City, County, and
State of New York, have invented, devised, and put
into practice, in the arrangement and construction of a Radiator
designed for burning coal or other fuel but more particu-
larly adapted to the use of Anthracite coal for the common
purpose of heating, some of which is distinguished by the
name of the Radiator or Globe Stove and that the following
is a full and exact description of the construction and operation
of said Radiator or Globe Stove as invented, or improved
by me -

Upon a cast iron circular bar, or about thirty
inches in diameter stands two cast iron shafts or iron columns
about three inches in average diameter, twenty inches in height
and about the same distance apart. Upon these columns stands
a number of arches of cast iron made hollow and round
of about three inches in diameter. The feet of said arch
which rest upon the tops of said columns are forced into
hollow globes about five inches in diameter which are cast in
globes fitted with each half of the arch and are joined
independently through the centre with the arch. The

point being covered by a filling about three eights of an inch wide cast into upon the edge of one half of the arch which laps its width upon the edge of the other half. The pointed corner of said arch is formed into a hollow cylinder about eight inches in height, and said in diameter upon its top and bottom with a paper about three or four inches in height and the said two diamonds projecting at right angles from the centre of said cylinder in a horizontal position and forms the tube which receives the first end of the steel straw pipe. Upon the said two diamonds of said small globes which forms the feet of said rock as before described are flanked openings about three and a half inches in diameter. Upon the said flanked and filled semicircular cylindrical caps, which covers said stated openings and binds the feet of said rock together a ring forming a cap surcasing is fitted upon the top of said curved cylinder which performs the office of hoop to bind the rock and curve cylinder together and forms also a band to support the water pipe which stands centrally upon said curved cylinder covering with its side the upper head and opening of the same. The interval of said straw about eight inches in height of ordinary straw and its uses about one yard capacity. The upper section which forms to cover to be removed at pleasure. The principle use of said straw is to contain water for evaporation. It also assists in giving a perpendicular finish to the most elevated portion of the stone. It would be susceptible that the mass with its aqueous parts is composed ^{only} ~~mainly~~ ^{mainly} of straw pieces gathered of other straws and caps before mentioned which used to bind said rock cylinders globes together. It is fastened downward by two or more rods and screws through the rock and the joint set in feed cement. Through

each of said hollow columns passes a rod or bolt of about
half-inch round iron having a few suitable heads within
the globular feet of said arch which being placed regaled
upon said column the bottom end of said rods pass down
through holes in the arch placed centrally under the ad-
jacent, and having screws cut upon their ends upon which
suitable seats are placed which are being sufficiently紧
to the said columns and arch and all firmly bound to-
gether in their proper positions centrally under the arch
is suspended a hollow iron shell or sphere made
in two hemispheres, and joined horizontally near
the center with flange or openings at the top bottom and
sides, & poles. The said openings are the said diameter
and directly opposite of those on the inner sides of the said
globes as before described. Through which openings pass
two thumbs or thin tubes as large as the aforesaid openings
will admit with their ends flattened and grated
and passed from the side into the feet of said rods where
they are secured by bolts having their heads in the larger
globes passing horizontally and centrally through said tubes
and cylindrical caps as before mentioned having screws
cut upon their ends upon which recessed seats are placed
which are being properly secured up the said small tubes
designed to keep the said from falling into the said
small globes are brought into their places at the same
time binding the said thumbs and cylindrical caps
firmly upon said small globes securing them and
the bottom section of said arch giving the possibility
of spreading at the same time suspending the recessed
or large globe in a proper position by means of the
aforesaid thumbs which are fitted places through
which a portion of the draught passes to the small
globes through the arch to the crown cylinder and pipe

as before mentioned. The upper hemispherical part of the globe is held with a band of flaunch upon its rim which fits closely over that of the under one covering the joint and giving it strength to which is added two brackets on each side of the lined side or edge of the hollow section of said globe by which means the two sections are drawn and held firmly together.

The base of the crown cylinder fits upon its corresponding necking or flaunch around the opening and the top of the globe in which situation it is held and the joint concealed by an ornamental cast iron collar forming a hoop for the base of the crown cylinder and the flaunch of the globe. It then turns nearly a right angle inward and forms a special base collar about two inches wide and two and a half inches high, the upper section of the globe being centered crown cylinder from the center of the base and also the flaunch rising through which the fuel is introduced. The under hemisphere of the globe is elongated about four inches below the regular curve of the globe in form of the base portion of a balloon for the purpose of aiding the ascent of the vessel and diminution of the grate. The opening is about six inches in diameter and precisely corresponds with the top or convex cylinder which is about one foot high and rising on the top round from with a suitable shrubbing encircling its base from which extends a flaunch about one half inch wide intersected with ventilating holes about one and a quarter inch in diameter which is designed to admit atmosphere necessary to supply combustion. Directly over this projected rim or flaunch is placed a corresponding cast iron ventilator rim with the same number of perforations equal distant from each other in diameter. The office of this rim which holds the ventilator is to control the air.

bottom of the fuel in the stove which is effected by giving it a slight circular movement to the right or left by which the oscillating holes are thrown open partially or entirely closed. Which is designed to sufficiently control the quantity of the stove heat regulate its temperature of the heat. The ash pan which is buried the bottom is about 12 inches wide by sixteen in length to be drawn out sideways it is inclined in the front so as to fall singly to the pan open only and the side from which the pan is drawn this case may be cast entire with the heat in separately or pounds of sheet iron in the side and the upper edge riveted to the bottom or under side of the heat which is about six inches from the floor pipe into no fuel of ordinary construction.

The horizontal pipe which passes from the crown cylinder is flattened or depicted horizontally so as merely to correspond in width with the diameter of the crown cylinder. So the bottom of the pipe is fitted a horizontal damper made to slide inward and close the diameter of the crown cylinder when necessary which case it passes wholly through the pipe into the nest passing in the crown cylinder above said damper by which it is much diminished and the combustion proportionately reduced. I have varied the form and arrangement of the asbestos flues of said stove by passing horizontally around the pipe forming a circular platform in which the draft passes from the side ascending thereby column into an arch to the pipe by which the structure of the stove is more elongated and more heat discharged immediately in consequence of an increased surface. I have in this case dispensed with the side flumes and have varied the form of the heat in the style of a fashionable centre table bottom I have varied the form of my grate to accommodate

into the different sizes of very stones although of such a thin
size may suffice, both purposes. The track and pinion
gear is constructed as follows. It is made of cast iron
of a circular form about eight inches in diameter in form
of a wheel with the pins riveted. The center
is hub is about one inch thick but not elevated, or projecting
above the spokes or radiating bars of the gear which
are deepest in the center but grow thinner and wider
as they approach the extremity. This gear is placed hori-
zontally in a horizontal position, in the bottom section of the globe
and to its center is firmly secured a pack about one
foot in length, quartered of an inch thick and two inches
wide with a slot in its center nearly its whole length
about three quarters of an inch wide with a slot on one
side of proper dimensions to receive a pinion wheel
placed horizontally through the center column and said
pack and hub secured by a crank-handle on the outer
end of the hub and gear is raised up and down
slightly so the gear may be raised into the center of the
globe by the vibration, or a slight movement the ashes only
are discharged and in the latter movement when the pinion is
turned several times around the coal is precipitated into
the ash pan at pleasure. The bottom of the pack may be
covered in a sheet iron case to receive the coal work found
being dropped with the coal when the center column is small
instead of the pack a straight stem is cast in the grate or
tubular about eight inches long the bottom end of which fits
loosely in the end of a horizontal lever suspended through
one side of the center cylinder by moving this lever hori-
zontally the ashes are shaken out perfectly and by working
the said lever perpendicularly the grate is elevated in
the tube where it is larger and consequently allows the
coal to fall around its sides into the ash pan. This oper-

time is only necessary when there is an accumulation of cinders or slate in the stove.

The manner of operation or manner of filling and managing said stove is as follows. The wire being removed from the tube and furnace, which is furnished with a stove pipe inserted into the top of the oven, cylinder, through which the coal is thrown from the bottom into the large globe, a suitable quantity of ignited charcoal or light wood may first be introduced in the said coal may first be introduced in the heating pot upon the top by making a small opening in the center of the coal and when the heating is well ignited put small hard coal upon the top and replace the wire with a common draught wire which will become thoroughly ignited. The same process may be followed with success in handling when there remains a considerable quantity of extinguished coal in the stove which may frequently occur in the morning, - care should be taken to keep the ashes well shaken out to prevent the fire from clogging, and when burning too high the ventilator may be closed and the ashes damped. But as before mentioned by which means the fire may be perfectly controlled. The ashes and cinders being discharged in the described.

The improvements claimed in my invention are as follows, 1st. - claims the style, general arrangement and fashion of the above described Radiated or Globe stove believing the peculiar advantages of said arrangement and the generating and equal diffusion of heat exclusively confined to the globe or spherical furnace a receiver of fuel for the following reasons, 2d. - As the only fire from which heat can be equally radiated and consequently it has the best and advantages of insulating and helping off heat downwards, warming the floor and loca-

region of atmosphere which cannot be affected by the angular or cylindrical flame.

Secondly) Contains the spout or hollow globe, in which the hollow end of the bottom section is punctuated as a reservoir of fuel and radiator of heat, in combination with the vibrating and heating grates as before specified together with the said central hollow column which prevents the escape of ashes into the road in its descent from the globe to the side pan.

Third and lastly. I claim as my improvement, separately and as a part the said or spout or vibrating and heating grate as before specified.

In witness whereof I have hereunto set my hand this eleventh day of December 1833.

Witnessed
Mr A. South
